UNITED STATES PATENT OFFICE.

FRANK A. ROSS, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A CASING FOR TRAVEL-INDICATORS FOR VEHICLES.

44,618.

Specification for Design.

Patented Sept. 2, 1913.

Application filed February 14, 1913. Serial No. 748,459. Term of patent 14 years.

To all whom it may concern:

Be it known that I, FRANK A. Ross, a citizen of the United States, residing at Chicago, in the county of Cook and State of Illinois, have invented a new, original, and ornamental Design for Casings for Travel-Indicators for Vehicles, of which the following is a specification, reference being had to the accompanying drawings, forming a part thereof.

The drawing is a face view of the casing of a travel indicator showing the three dial

plates, assembled in accordance with my new design.

I claim:—

The ornamental design for a casing for a travel indicator as shown.

In testimony whereof I have hereunto set my hand at Chicago, Illinois, this 12th day of February, 1913.

FRANK A. ROSS.
